WATER HEATER

James F. Walsh, Cleveland, Ohio

Application March 9, 1935, Serial No. 10,139

2 Claims. (Cl. 257—235)

This invention relates broadly to a means for heating water in a heating system for domestic use.

One of the objects of the invention is to provide a water heater of self contained character particularly applicable for utilization of waste heat of combustion from heating furnaces and/or waste heat of steam.

The novel features which I believe to be characteristic of my invention are set forth with particularity in the appended claims.

My invention itself, however, both as to its organization and method of operation, will be best understood by reference to the following description taken in connection with the accompanying drawing.

It will be understood that the principles of my invention may be embodied in various forms, and that exact details are not material. The present invention, therefore, is to be considered as merely indicative.

The form illustrated in the drawing and hereinafter described in detail has been found to be one of the practical embodiments and capable of efficient operation and practical in construction for use with hot air furnaces, and with slight modifications in a steam line.

In the generation of steam in a boiler, or hot air in a hot air furnace, the escape of high temperature flue gases by way of the chimney is a source of considerable waste. This waste may be minimized by the installation of the water heater, the subject matter of this invention, the function of which is to take heat from the waste gases, or steam if placed in a steam line, and impart it to the water in the heater. Besides acting as a fuel saver, this means provides a large reserve of hot water to meet domestic demands.

Referring to the drawing:

Fig. 1 is a central vertical longitudinal section, partly in elevation of a construction and arrangement for accomplishing the objects, of my invention, shown in connection with a conventional heating unit A and a gas water heater B.

The same part is designated by the same reference character wherever it occurs in the drawing.

In accordance with my invention, I employ an outer shell 10, preferably square in cross section, and an inner shell 11 also square in cross section. The end 12 of the inner shell 11 that enters the stack opening 13 may be drawn from a square to a round formation so as to enter a round opening leading into the chimney.

The outer shell is held in spaced relation with

the inner shell by means of the ends 14 and 15. The space 16 is utilized to accommodate the water that entirely surrounds the inner shell. The inner shell is provided with staggered water circulating tubes 17; 17; 17 that extend across the passage 18 in the inner shell 11, against which the hot gases impinge and pass on their way to the chimney.

The outer shell is so constructed that each tube may be readily examined, by simply removing the 10 plugs 19; 19; 19; 19 therein and holding a light at one end and looking through the tube from the other.

In steam generator or hot water practice the rate of heat transmission is much less than 15 would be expected, and this is apparently due to something in the nature of a stationary film of gas on the one side, and of water on the other through which the heat is transmitted at much less rate than through metal. The rate of transmission through such film is much more rapid 20 on the water than on the gas sides, as water carries heat more quickly than gas.

It is well known that the employment of projections, baffles or retarders in flues, by breaking 25 up the gases, undoubtedly helps to destroy the gas film and assist heat transmission, to accomplish this feature I stagger the water circulating tubes.

One of the great advantages of this heater is 30 that it may be shortened when constructed to make a very squat heater, making it particularly suitable where space is limited.

The feed water may be introduced into the bottom of the water chamber by the piping 20, 35 and practically throughout the whole course of its progress through the chamber is travelling in a direction opposite to that taken by the gases, thus ensuring a very efficient heat transfer 40 throughout the whole inner surface of the chamber. The hot water may leave the heater through a pipe circuit as at 21.

The water circulating tubes are installed as follows, a description of the installation of one will suffice for all. In the internal shell 11 there 45 is provided a series of openings 22; 22; 22; 22; diametrically opposite each other. The ends 23, 23, 23, 23, of the tubes are fitted with a thread 24, 24, 24, 24, and nuts 25, 25. Under each nut there is provided a suitable washer as at 26, 26. The 50 tube being mounted in place, the nuts are tightened against the washers, and the tube is secured in place. With this method it is unnecessary to head over or expand the tubes in the holes in the plate. Each tube has its full area for escape of 55

water, hence the circulation is rapid, free and continuous, so obviating gulping or pocketing in the tubes.

The inner shell 11 is provided with an inlet 21. This inlet is connected in any suitable manner to a hot air furnace of conventional type such as at A. The inlet pipe projects into the shell 11 as at 28, having directly thereabove a manually operated valve 29, having a heat resisting face 30. This valve is normally housed in a hollow projection or valve-chest 31 of suitable cross-section to receive the construction shown.

The valve chest is provided with a cap 32, screw bolts 33 serving to fix the cap in position. The 15 threaded stem 34 of the valve is threadedly mounted in the cover. The valve 29 is mounted for free rotation on the valve stem 34. The end of the shell is closed by a removably mounted plate 35. The shell is also provided with a drain outlet pipe 36, having a removably mounted cap or closure 37 thereon. The shell at this particular end may be provided with an opening 38 adapted to accommodate a stove pipe 39 connected to a gas water heater of conventional 20 design such as B.

The hot water supply pipe 40 may be piped directly through the chamber in the shell 11 from the storage water heater of the gas water heater B, the purpose of which is hereinafter set forth.

30 The other end of the shell is provided with a damper 41. This damper has a dual function, first as a draught regulator, and second as a valve. It is used as a valve in the washing operation of the chamber hereinafter explained.

35 The hot water piping 40 may communicate with the nozzles 42 and 43, having a suitable control valve 44 therein to control the water. The nozzles are given a pitch downwardly and upwardly toward the inlet, or where the flue gases enter the chamber. Obviously the nozzles may be positioned around the inner perimeter of the chamber so that belts or zones may be cleaned if desired. The inflow of the cold water and the outflow of the hot water may be altered to meet 40 the exigencies of use, and further the washing system may be changed from the hot water line to the cold water line.

45 In the summer season, a stove pipe 39 may be connected to the chamber in the opening 38, and 50 the flue gas utilized to assist in heating the water in the pipe 40 that may pass through the chamber, thus the flue gas from the gas water heater acts as an auxiliary to heat the water.

55 In the summer season the valve 29 is screwed down to close the inlet opening thus cutting off the furnace proper from the heater.

The gas water heater may be connected to a suitable gas supply through piping 45 having a gas burner 46 connected therewith.

60 The washing out of the heater is accomplished as follows. The valve 29 is screwed down to close the inlet 27 to prevent the water from finding its

way back into the inlet, and hence into the furnace. The draught regulator 41 is closed to prevent the water or steam getting into the chimney. The cap 31 is removed from the drain outlet leg 36. The control valve 44 is released to let the water into the chamber where it is delivered against the interior wall of the chamber thus removing the soot therefrom with approximately the same thoroughness as if it were manually scraped therefrom. The water with the soot is carried off through the drain pipe and conducted away through the sewer by any convenient arrangement of piping (not shown).

To scrape the interior of the chamber the cap 15 35 may be removed to give access thereto.

While I have herein shown and described a preferred arrangement, it will be readily understood that changes and modifications therein may be found desirable or essential in meeting the various exigencies of use, and I desire to be understood as reserving the right to make any and all such changes or modifications as may be found desirable or essential, in so far as the same may fall within the spirit and scope of the invention as expressed in the accompanying claims when broadly construed.

Having thus described my invention, what I claim is:—

1. An apparatus for generating hot water for domestic use, comprising a rectangular chamber having an outlet, a damper located in the chamber at the outlet, an inlet pipe projecting into the chamber, a valve normally inactive above the said inlet pipe and adapted to close the inlet, removably mounted circulating tubes extending across the chamber in staggered formation so that the flue gases entering said chamber may be influenced uniformly around the perimeter of the said chamber, an outer rectangular shell surrounding the chamber and held in spaced relation therefrom and having its ends secured to the chamber, said surrounding shell being provided with openings opposite said circulating tubes, plugs to close said openings, means in the chamber whereby the chamber may be washed, and a drain pipe to drain the chamber after washing.

2. An apparatus for generating hot water for domestic use, the combination of an inner flue shell having an inlet and an outlet, an outer shell encircling the inner shell and forming a chamber therearound for receiving a fluid to be heated, removably mounted tubes passing transversely through the inner shell, openings in the outer shell in alignment with said tubes, removable plugs in said openings, a removable closure plate on one end of the inner shell, a valve adapted to close the inlet, a draft regulator adjacent the outlet, a drain pipe, said drain pipe adapted to drain the inner shell after washing, and means for admitting fluid into the inner shell whereby the same may be washed.

JAMES F. WALSH.
